UNITED STATES PATENT OFFICE.

MAXIMILIAN WEIL, OF NEW YORK, N. Y., ASSIGNOR TO SAFETY RAILWAY CONTROL COMPANY, INC., TRUSTEE, A CORPORATION OF NEW YORK.

AUTOMATIC SAFETY-SIGNAL SYSTEM.

1,247,915.

Specification of Letters Patent.

Patented Nov. 27, 1917.

Application filed May 23, 1913. Serial No. 769,410.

To all whom it may concern:

Be it known that I, MAXIMILIAN WEIL, a citizen of the United States, residing at New York city, in the county of New York 5 and State of New York, have invented certain new and useful Improvements in Automatic Safety-Signal System, of which the following is a full, clear, and exact specification.

10 The object of this invention is to provide a simple means for automatically controlling or signaling trains, as at curves, crossovers, etc., which may be controlled by the automatic block signal system, or other systems at present used. The invention is preferably carried out by insulating the locomotive from the tender, or from the remainder of the train, in combination with the insulated track joints now commonly used 15 20 in connection with automatic block signal systems. A source of electrical energy is carried by the locomotive, and suitable devices are placed in series with this source of energy on a normally closed circuit so arranged that the running rails will form a part of same. As long as the circuit remains closed and undisturbed the control of the train is entirely in the hands of the engineer, but a disturbance in the closed circuit including the rails causes the control of 25 30 the train to be taken out of the engineer's hands, or a signal effected. A break in the closed circuit on the locomotive takes place when the locomotive passes over the insulated joints on the track. In case the track ahead is clear, a suitable path is provided for the locomotive current around the insulated joint, as by means of an ordinary track signaling relay.

35 40 45 Since it takes at least one-fifth of a second to cause the operation of a well designed magnet, and since a train going 60 miles per hour would travel 10 feet in about one-tenth of a second, the momentary rupturing of a controlling circuit as the train passes over insulated joints at a danger or signal point would not suffice to effect certain operation of even the best designed electroresponsive devices, because such devices cannot instantaneously operate, but always lag. This is because of hysteresis, that is the flux will not instantly follow the magnetizing current, and hence there will still be a magnetic flux when the current is zero.

In order to cause a magnet to instantaneously operate, a negative magnetizing force must be applied, that is, the current must be instantaneously reversed.

According to my invention, I have devised means for instantaneously reversing the current in a magnet or relay, and thereby causing it to be so quickly deenergized that it will be responsive even to a momentary interruption of the current. It thus becomes applicable for very high speed work, especially in railway signaling or automatic train control in combination with present signaling or control systems. More especially, the invention comprises means for connecting a relay or magnet with a single source of energy and an externally controlled circuit including the track rails, whereby the magnet will remain energized for certain conditions, and for others will be reversely magnetized and thereby caused to stop the train or actuate a signal.

In the preferred form of the invention shown herein, the train circuits comprise three legs of a Wheatstone bridge, with a source of current connected across the opposite ends, the relay or magnet across the middle, the fourth leg being constituted by the track rails and separated wheels. The respective resistances of these circuits are so proportioned that the interposition of an insulated track joint between the separated wheels effects reversal of the current through the magnet with instant repulsion of its armature, thereby effecting the signal. The invention lends itself especially for use in track signaling systems wherein a track relay opens the circuit around the insulated joints at normal danger position, thus causing instant operation of the train device when the first wheel opens the fourth arm circuit at a track joint. By this invention, the device operates by travel in either direction without the use of reversing switches and with the same source of current.

In the accompanying drawings, 100 Figure 1 is a diagram of the train apparatus, designed for stopping the train;

Fig. 2 is a simplified diagram;

Fig. 3 is a modification with an improved safety arrangement;

Fig. 4 shows the invention arranged to utilize a single source for both the operating and detector magnets;

Fig. 5 is a diagram of the track circuits;

Fig. 6 is a diagram of the track circuits for electric railways; and

Fig. 7 is a modification of Fig. 1, wherein 5 a different method of insulating the separated wheels is employed.

In Figs. 1 and 2, like symbols represent like parts. Instead of having the bridge arms A, B and C idle, the arms A and B 10 form the windings of magnet W and are so wound that their magnetic fluxes will aid each other. The arm C comprises a relay to guard against an open circuit in the arm C, the battery J being placed in series with 15 the armature 35 of relay C, so that if anything should break in the circuit in any of the arms, it will result in the application of the brakes. The "detector relay" D is provided with two armatures (see Fig. 1) 20 and is connected across E and F and is supplied with power through its own contact 36, so that if the armature I should drop, the detector relay D will have to be re-energized by hand before it will again 25 draw up its armature I. The relay D has also an armature 37, which is actuated together with armature I and the armature 37 is in series with the battery J, so that if 30 relay D is actuated, battery J will be open circuited, thus deenergizing everything in the circuit. The restoration of the armatures I and 37 of the detector relay D may be accomplished by providing the normally 35 open circuit switch 17, the depression of which will connect the contactor 38 with contact plate 39, and the contactor 40 with contact plate 41. The contactor 38 and the contact plate 39 will bridge the contact point 36 and armature I of the detector 40 relay D, whereas the contact 40 and contact plate 41 will bridge the open circuit in the main line of the battery J. The switch 17 can of course be located any place outside 45 the locomotive, if desired, so that after the detector relay D has once been operated, the engineer would have to dismount to replace everything to normal position. A suitable speedometer 16 may be provided and placed in series with the contactor 40 50 and contact plate 41 and so arranged that the contact points 42 and 43 will close only at a predetermined speed, such as 20 or 25 miles an hour as the case may be, so that if the switch 17 be located in the locomotive 55 cab, and if the detector relay D has been operated, even though the engineer might press down the switch 17 to restore everything to normal position, he will not be able to do so until the speed of the train has reached a certain predetermined low speed. Such an arrangement has many advantages, and further serves as a speed control around curves, cross-overs, etc. The operation of 60 one form of mechanism for venting the train line 2 is as follows: The cylinder 8 65

is supplied with air from the reservoir 4, through the pipe 5, then through the opening 13, then through pipe 6. The piston 10 having much greater area than the piston 11, will force piston 11 to the right notwithstanding that pipe 7 supplies air from the train line 2 in opposition to the air pressing on piston 10. If the magnet W is deenergized, valve 17 will close and valve seat 15 will open, shutting off the air from reservoir 4, and at the same time connecting the cylinder 8 with the atmosphere through the pipe 6 and the slot 14, which is cut into the stem of valves 15 and 17. The air pressing on piston 11 with the aid of the spring 12 70 will force the piston 10 back into the cylinder, thus exhausting the train line through exhaust 9. As soon, however, as the magnet W is reenergized, it will be seen that everything will be restored to normal position. 75

In Fig. 3, a separate source J² is employed for operating magnet W, the arm B in this case comprising a relay whose armature 50 is in series with battery J², 80 armatures 35 and 37, so that the opening of the circuit at any point causes W to be deenergized and the brake applied, or other signal to be made, where it is not desired to stop the train. 85

In Fig. 4, a single source J is used, as in Figs. 1 and 2, but the arms of the bridge are not employed to constitute the windings of operating magnet W. 90

As stated above, no additional apparatus is required upon the roadbed and the clearing and setting to "danger" by the insulated joints and track relays which are now used in connection with automatic block signals will be understood by referring to Fig. 5. 100 The joints now used with the signals and the batteries 22 and 23 are also batteries that supply power to the track relays 26. In order to provide a path for the current of the control system on the locomotive as 105 it passes over the joints 67 and 68, in case the track ahead is clear, the wires 60 and 61 are provided and are short-circuited by the track relay 26 in block Z through the wires 64 and 65. The object of connecting 110 the wires 60 and 61 diagonally across the joints is to provide means for detecting the failure or break-down of the insulation of either joint 67 or 68. It will be seen that while the relay 26 in block Z short-circuits 115 the wires 60 and 61, should the insulation of joint 67 break down, the wires 60 and 61 will place the track battery 22 on a short-circuit, which will act the same as though 120 there were a train in the block X, thus putting the track relay of block X to "danger," as well as the automatic control system. Again, should the insulation of joint 68 125 break down the battery 23 of the block Y will be placed on a short-circuit, which will 130

deenergize its relay 26, causing everything in the block X to go to "danger." Should the insulation of both the joints 67 and 68 break down, both of the batteries 22 and 23 would be short-circuited, again placing everything in blocks X and Y to "danger." The relay 69 is placed across the wires 60 and 61 and is of high resistance. This relay is normally deenergized, and its armature is in series with the track relay 26, so that should a small leakage take place across the joint 67 or 68, while the wires 60 and 61 are not short-circuited by the armature of the track relay 26 in the block ahead, the leakage current across the insulated joints 67 and 68 will draw up the armature of relay 69, thus open-circuiting track relay 26 and setting everything to "danger" in the block behind. It will be seen, however, that the relay 69 is not essential and that the short pieces of wire 60 and 61 will be sufficient to bring about the desired results.

In Fig. 6, is shown an adaptation of the invention for electric railroads using one or both rails for both propulsion and signaling currents. Either an auxiliary wheel insulated from the other wheels, or one truck insulated from the others will be used, because the reactance bonds used for the signaling currents short-circuit the insulated joints at all times. A short section Q of insulated rail is provided at each block, the length being less than the distance between the insulated wheels. As the wheel passes over this short section Q, it will become isolated, and open the fourth arm of the bridge, as before described. One auxiliary wheel will be sufficient, if insulated from the other wheels, in connection with a rail section Q, but where the truck is insulated from the other wheels, a second section L will be provided in the other rail. Jumpers 70 carry the propulsion and signaling currents around the sections Q and L. Wires 71, 72, lead from Q and the jumper 70 of the other rail, and are connected to armature 73 and contact 74 of alternating current relay 75, which short-circuits 71, 72, in case the block ahead is clear, and opens 73, 74, when the block is occupied. In case of failure of the insulation of joints of rail section Q, the wires 71, 72, will short-circuit reactance bond 76, thus opening relay 75 in the block behind, and making the danger indication. Wires 77, 78, connected respectively to the rail containing section Q, and section L, and to contact 79 and armature 80 of relay 75 performs a similar function for the insulation of section L.

It will be seen that the system is extremely simple and requires nothing more than two simple magnets on the locomotive, and the insulation of the locomotive from the tender. Since a locomotive does not require automatic control when going alone, the insu-

lation of the locomotive from the cars is accomplished, by insulating the two couplers of the locomotive, that is, the front coupler and the rear coupler on the tender as shown in Fig. 7. Whenever a locomotive 70 is coupled to a car or a train of cars, the air lines are connected together and the valve y is opened to admit air into the train lines. Whenever it is uncoupled from any car or train of cars, the valve y must be 75 closed. It is this opening and closing of the valve y which I make use of in simplifying the insulation of the two bodies. The point F of the Wheatstone bridge is brought to the contact plate R, and also to the coupler T of the locomotive, which is insulated at V as shown. The point G of the bridge is brought to a contact plate R' in front of the locomotive and thence grounded through the valve and wheels. The valve handle of valve y carries a contactor S, which engages the contact plate R, when the valve is closed and disengages it when the valve y is opened, so that if the train is coupled to the locomotive as shown in Fig. 80 90 95 100 105 110 115 120 125 130 135 140 145 150 155 160 165 170 175 180 185 190 195 200 205 210 215 220 225 230 235 240 245 250 255 260 265 270 275 280 285 290 295 300 To test the coupler insulation, the point E of the bridge is connected to a contact plate 81 at one end, and 82 at the other end. 83 is an insulated contact carried by the valve handle. As shown, the rear coupler T is now connected to the point F of the bridge, whereas the front coupler T' is connected to the point E, and the point G of the bridge is grounded to the locomotive 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 6

frame. The point E being connected to the coupler T' places the insulation V' under a continuous test, and should it break down, it will short-circuit the detector relay D, causing the operation of the brakes. As soon as the locomotive is uncoupled from the car, the air valve must be closed, thus connecting the point F to the locomotive frame, and the point E to the rear coupler 10 of the tender placing the insulation V under a continuous test. In this way the insulation of both the front and rear couplers will always be under test before it is coupled to any car.

15 The detector relay in the several forms is placed across the points E F of coils A B C arranged on the principle of the Wheatstone bridge and supplied with current by the single battery J. The fourth arm of the bridge is made up of the tender and locomotive wheels and the running rails. Normally the fourth arm of the bridge, as was stated above, is made up of the running rails and the locomotive wheels forming a transient current circuit of negligibly low resistance until the locomotive has reached the insulated joints K, which joints in case of the track ahead being occupied turn the fourth arm of the bridge, normally of negligibly 20 low resistance, into a very high resistance arm. If the resistance of this fourth arm changes from a negligibly low value to a high value, the current through the relay D will be reversed. Without going into a mathematical analysis to show that the current through relay D will reverse when the fourth arm of the bridge is made to have a high resistance, it can readily be understood by remembering that normally the fourth 25 arm is of so low a resistance that it may be assumed to be *nil* as compared with the resistance of the other arms of the bridge. Therefore the points G and F may be considered as being connected together, in which case there will be two circuits connected in multiple supplied by the battery J, one of the circuits being made up of coil B, whereas the other circuit is made up of coils A, D and C, D and C being in multiple. If the 30 circuit through the rails is now opened the current cannot go through the fourth arm and will therefore take a path through the coil C, then through D in a reverse direction and back to the battery through coil B. The resistances A, B and C are so adjusted as to give the desired value of a reverse current which will supply the desired demagnetizing force. It is best to adjust the resistance so that the negative magnetizing 35 force will be greater than theoretically necessary for the hysteresis curve in that case would have to pass through the zero line at the time the armature operates. When the current through relay D reverses, neutralizing the stored magnetic energy of relay D,

it will not only release the armature I and subject it to the force of gravitation or of a spring (if a spring be used), but it will also set up a force of repulsion which will tend to "kick off" armature I, thus causing 70 the operation of same to take place instantaneously.

Since the operation of the system depends upon the integrity of the insulation between the two bodies, (separated wheels) means is 75 provided for detecting any failure of such insulation. In case of the locomotive being insulated from the tender, the locomotive coupler M is insulated from the remainder of the locomotive as shown at O and the 80 tender coupler N is insulated from the remainder of the tender as shown at P. This leaves the section O P electrically insulated from the remainder of the locomotive and tender and is made use of as a ground detector. By connecting same to the point E by the wire 87 it will be seen that while this wire connects the section O, P with the point E, should the insulation either at O or at P break down, the wire 87 will short-circuit the relay D, thus deenergizing it, causing the operation of magnet W or any other signal device that may be placed there to be operated by the relay D.

It will be seen that there is no apparatus 95 of any kind required on the roadbed or in connection with the signals, and that the whole system is mounted on the locomotive. It will also be seen that the system is extremely simple consisting merely of two 100 magnet coils D and W, and that it does not make any difference in what direction the locomotive is running, that is to say, whether the boiler goes first, or the tender goes first. It will be further seen that a variation in the E. M. F. of the source J will not affect the operation of the system in the least, since one and the same E. M. F. is made to supply a normal running magnetizing force as well as a negative or de-magnetizing force.

From the foregoing description, it will be seen that the invention comprises broadly an electroresponsive device, such as a magnet or relay, which will be instantaneously 115 deenergized upon even a momentary interruption of its controlling circuit, by a novel application of the Wheatstone bridge principle, wherein the fourth arm of the bridge is connected, for signaling or train control purposes as herein described, with an externally controlled track circuit. While I have described a preferred embodiment of the invention in combination with means for automatically stopping a train, the invention is not so restricted, as it is 120 fully within the scope of my invention to cause the detector magnet D to operate a signal of any desired character, or to cause such detector magnet to control any device 125 130

which may be desired. It is also to be understood that the Wheatstone bridge circuits and the detector magnet are not in all cases to be carried on a moving vehicle but can be placed wherever an instantaneously opening relay is desired for signaling or control purposes.

Various modifications and changes may be made within the scope of the appended 10 claims without departing from the spirit of the invention.

Having thus described my invention, I declare that what I claim as new and desire to secure by Letters Patent, is:—

1. The combination in a railway system 15 with an electroresponsive device and a source of current, of means controlled by the condition of the track for reversing the current therein from said source to effect operation of said device, said means comprising connections arranged in the form of a Wheatstone bridge.

2. The combination in a railway system 25 with an electroresponsive device and means for energizing it to indicate a normal safety condition, of means controlled from a distance including the track rail and a traveling contact for effecting a reversal of the current to said device without opening the 30 circuit from said energizing means to effect a danger indication.

3. The combination in a railway system 35 with an electroresponsive device and means for energizing it to indicate a normal safety condition, of means including the track rail controlled from a distance for effecting a reversal of the current to said device by varying the resistance of the track portion 40 of the energizing circuit without opening the circuit.

4. The combination in a railway system 45 with an electroresponsive device, and a signal controlled thereby, of means for energizing said device to effect one indication of said signal, said device being connected across the arms of a Wheatstone bridge, and means for varying the resistance of the track rail comprised in one of the arms of said bridge to reverse the current through said 50 device and effect another indication of said signal.

5. The combination in a railway system 55 with a vehicle carrying an electroresponsive device, of means for energizing said device, including the arms of a Wheatstone bridge, and means including the track rail for varying the resistance of one of said arms to effect reversal of current through said device.

6. The combination with a vehicle carrying 60 an electroresponsive device, of means for energizing said device, including the arms of a Wheatstone bridge, one of said arms including the running rail, and means for varying the resistance of said running rail

arm to effect reversal of current through said device.

7. The combination with a vehicle carrying 70 an electroresponsive device, of means for energizing said device, including the arms of a Wheatstone bridge, one of said arms including separated traveling contacts on the vehicle and contacting with the track rail, whereby variation of resistance of said latter arm reverses the current through said device and effects operation thereof, and a track circuit and controller therein for varying the resistance of the circuit including the track.

8. The combination with a vehicle carrying 80 an electroresponsive device, of means for energizing said device, including the arms of a Wheatstone bridge, one of said arms including separated traveling contacts on the vehicle and contacting with the track rail, whereby variation of resistance of said latter arm reverses the current through said device and effects operation thereof, and means external to the vehicle for varying the resistance of said track rail circuit.

9. The combination with a vehicle carrying 85 an electroresponsive device, of means for energizing said device, including the arms of a Wheatstone bridge, one of said arms including separated insulated traveling contacts on the vehicle and contacting with a stationary conductor, whereby variation of resistance of said latter arm reverses the current through said device and effects operation thereof, and means automatically 90 detecting a ground between said separated traveling contacts.

10. The combination with a vehicle carrying 95 an electroresponsive device, of means for energizing said device, including means for reversing the current to effect operation thereof, said means including in part separated insulated wheels and the running rail, and means for actuating said device upon 100 opening the rail circuit, distant signal controlled means for controlling said rail circuit, and means for actuating said device upon connection between said separated wheels.

11. The combination with a train comprising 115 a plurality of cars, coupling means, one of which is insulated, a fluid pressure line for said cars, coupling means therefor, and means on each car for controlling its fluid pressure line, of an electroresponsive device on one of said cars, means for energizing it, including means connected to the other car and the track rail for reversing the current to effect operation thereof, said current reversing means being controlled by the 120 coupling of the cars and of the fluid pressure lines.

12. The combination with a train comprising 125 a plurality of cars, coupling means, one of which is insulated, a fluid pressure 130

- line for said cars, coupling means therefor, and means on each car for controlling its fluid pressure line, of an electroresponsive device on one of said cars, means for energizing it, including means connected to the track rail for reversing the current to effect operation thereof, said current reversing means being controlled by the coupling of the cars and of the fluid pressure lines, and being ineffective when the cars are uncoupled.

13. The combination with a train comprising a plurality of cars, coupling means, one of which is insulated, a fluid pressure line for said cars, coupling means therefor, and means on each car for controlling its fluid pressure line, of an electroresponsive device on one of said cars, means for energizing it, including means passing through the track rail for reversing the current to effect operation thereof; said current reversing means being rendered effective when the cars are coupled and the fluid pressure lines connected, and ineffective when the circuit between said cars through the rail is interrupted, and means controlling the track portion of the circuit.

14. The combination with a vehicle carrying an electroresponsive device and means for energizing it, of connections including resistance current reversing means for effecting operation of said device, said re-

sistance means being in part the track rail, and means for effecting operation of said device upon breaking down of said external track resistance. 35

15. The combination with a vehicle carrying an electroresponsive device and means for energizing it, of connections including resistance current reversing means for effecting operation of said device, said resistance means comprising an insulated track joint located externally of the vehicle, traveling contacts carried by the vehicle and means for effecting operation of said device 40 upon breaking down of said track joint. 45

16. The combination with a vehicle carrying an electroresponsive device and means for energizing it, of connections including resistance current reversing means for effecting operation of said device, said resistance means comprising an insulated track joint located externally of the vehicle, traveling contacts carried by the vehicle and means for effecting operation of said device 50 upon breaking down of said track joint, and a signaling relay controlling a circuit around said track joint. 55

In testimony whereof I affix my signature, in presence of two witnesses.

MAXIMILIAN WEIL.
